UNITED STATES PATENT OFFICE.

CHARLES WARD HALL, OF LARCHMONT, NEW YORK.

MUFFLER FOR GAS ENGINES.

Application filed February 9, 1926. Serial No. 86,977.

This invention relates to a muffler for gas engines—more particularly for aircraft engines, although not necessarily limited thereto.

5 One object of the invention is to provide a muffler which will silence, or largely silence, the noise of the engine exhaust and at the same time will induce a strong suction during the latter part of the scavenging 10 stroke and thereby more completely remove the burnt gases and so permit of a less diluted fresh charge.

15 A further object is to provide a muffler which is simple in construction, and hence may be produced at low cost, and is also capable of being readily cleaned of deposited carbon.

With these objects in view my improved 20 muffler comprises, as its essential parts, a Venturi tube, an annular chamber which surrounds the venturi and is connected therewith by openings in its walls to the rear of the throat, and an inlet which at its outer end is adapted for attachment to the 25 engine exhaust port and thereby to support the muffler and which spreads the exhaust gases and delivers them into the annular chamber tangentially in a thin stream substantially from end to end thereof.

30 The volume of the muffler is preferably from two-thirds of to the full volume of the engine cylinder. The inlet, which at its outer end or intake is of the same size as the exhaust port of the engine, widens rapidly 35 therefrom in one dimension and in the other dimension narrows slowly to a slit, with a large and continuous increase in cross-sectional area, the discharge slit through which it connects longitudinally with the annular

40 chamber having an area preferably of from one and one-half to two and one-half times the area of the intake. The upper or outer side of the inlet is preferably tangent to the outer cylindrical wall of the chamber, and

45 its opposite inner side would, if extended, intersect the same. The annular chamber, formed between this outer wall and the Venturi tube and having an area of from two and one-half to four times the area of the inlet discharge slit, is closed at each end by 50 a partly conical stamping with short cylindrical extensions or lips at both ends, the two stampings serving to connect the venturi with and to support it co-axially within

55 the outer casing. The venturi has a smooth conical mouth section terminating forward-

ly in a short cylindrical lip, a short throat with parallel or preferably slightly rounded sides, and a much longer and more slightly tapering rear section which is perforated 60 by a number of holes and which, terminating in a short cylindrical lip, is extended by the rear conical stamping to the outer casing at its rear end. Suitable proportions for the venturi, for the use here intended, 65 are a mouth section with intake of from two to five times the area of the throat and with the angle of its cone not over thirty degrees, and a rear section which is from five to eight throat diameters in length to 70 the point where it connects with the conical stamping and at the extreme rear end of the muffler has an area of from five to twelve times the area of the throat.

The greater the ratio of the entrance and 75 of the discharge areas of the venturi to the area of the throat, the greater will be the suction produced for a given speed. As usual in any venturi the reduction in pressure is greatest at the throat, but is well pronounced throughout all the rear section. 80 Therefore, an open throat as the only exhaust outlet would produce the highest possible suction. This, however, while desirable as increasing the engine power, tends 85 to a too rapid discharge of the burnt gases to act as an effective muffler, since the maximum reduction of noise results from the slowest and most diffused exit of these gases. I accordingly provide mufflers of different 90 types merely by varying the perforations connecting the outer chamber with the Venturi tube. For one type, a muffler which will afford a maximum of silencing, there may be some two hundred to two hundred and 95 thirty small holes, having an aggregate area of from one and one-fourth to one and three-fourths the area of the inlet discharge slit, which are evenly distributed over the rear section of the venturi. The other type, in 100 which the venturi is perforated at or near the throat only and by a few, approximately a dozen, larger openings aggregating in area three-fourths to one and one-fourth the area of the inlet discharge slit, is less perfect as a silencer but is much more effective in exhausting the burnt gases from the engine cylinder.

105 A factor contributing to the efficiency of the muffler as a silencer is the substantially cylindrical form of the outer casing or muffler body and the tangential entrance pro-

vided for the exhaust gases, whereby the direction of these gases is changed without shock and the inertia of the first discharged high velocity gases carries them round and round the annular chamber so that on re-passing the entrance slit they help to accelerate the later portion of the discharge. At the same time the action of the venturi itself produces a minor secondary swirl in the exhaust for each of the small perforations, resulting in a very quiet discharge.

By removing three or four small bolts or rivets by which the forward end of the venturi is joined to the forward conical stamping, the venturi may be pushed out of the casing and the whole muffler readily cleaned of carbon without removal from the engine to which it is attached.

One practical embodiment of the two different types of mufflers is shown, by way of illustration and not of limitation, in the accompanying drawings, in which—

Figure 1 is a top or plan view of a muffler of maximum efficiency as a silencer, with parts of the outer casing and of the inner Venturi tube broken away; Fig. 2 is a side view of the same, also with a portion of the outer casing broken away; Fig. 3 is a view showing the muffler partly in rear end elevation and partly in section on the line 3 3 of Fig. 1; Fig. 4 is a view, in longitudinal section on the line 4 4 of Fig. 5, of a muffler of the second type, effective in exhausting the burnt gases; and Fig. 5 is a transverse section of the same on the line 5 5 of Fig. 4.

Referring to the drawings, the Venturi tube proper comprises an imperforate conical forward end or mouth section 11, which terminates in a short cylindrical extension 40 or lip 12, a short throat 13, and a rear section 14 which also terminates in a short cylindrical lip 15, of the same diameter as the lip at the forward end. The rear part of the tube shown in Figs. 1 to 3 is perforated 45 by a large number of small evenly distributed holes 16, and as shown in Figs. 4 and 5 is provided with a few larger openings 16' grouped together close to the throat. The venturi is mounted within and secured coaxially of the cylindrical outer casing 17 by means of the two like conical stampings 18 18, provided at their ends with short cylindrical extensions or lips 19 and 20, one of which stampings is fitted at its smaller forward end upon and secured, preferably by three or four small bolts 21, to the cylindrical lip at the mouth of the venturi and at its rear larger end by rivets within the forward end of the casing, closing the forward end 55 of the annular chamber 22, and the other stamping is fitted at its smaller forward end by a slip joint upon the cylindrical lip at the rear end of the venturi and at its larger rear end is riveted to the rear end of the casing, 60 forming a rearward extension of the Venturi

tube which closes the rear end of the chamber. The casing 17, as shown, is shaped up from a sheet of metal which is rolled up from one of its sides 23, which forms one side of a longitudinal opening, to nearly a complete cylinder and is left extending at a tangent from the other side of such longitudinal opening. This integral extension of the casing wall suitably shaped up, forms the upper or outer side 24 of the muffler inlet and at its flanged edges 25 is riveted or otherwise suitably secured to the flanged edges 26 of the opposite inner inlet side-piece 27, which is shaped up from a separate sheet of metal and at its inner end 28 extends inwardly somewhat beyond and is riveted to the flattened and slightly inturned side 23 of the casing. Where, as in the type of muffler shown in Figs. 4 and 5, the outer chamber is connected with the interior of the venturi only near the throat of the latter, the extended inner end of the lower inlet side-piece, within the chamber, is preferably curved outwardly as at 28', opposite the perforations in the Venturi tube, to deflect the exhaust gases away from these perforations and towards the ends of the chamber. The outer ends of the two inlet side-pieces are fitted in any suitable manner for attachment to the exhaust port of the engine for which the muffler is designed—as shown for example, for attachment to the oval exhaust port of a Wright engine, by providing them with outwardly projecting flanges 29 29' and building them up as at 30 with torch and wire to give both greater strength and greater heat conductivity, and drilling holes 31 at the corners of the flanges for the necessary bolts.

As shown, the muffler is adapted for attachment to a single cylinder of an engine of radial type and, of course, is to be so attached that its axis will be approximately in the line of the air stream; but one muffler may be connected through a suitable manifold to as many as three cylinders, provided that they are so timed that each cylinder completes its scavenging stroke before the exhaust valve of the next cylinder opens.

The muffler is not only simple in construction, having few parts which are readily assembled, but is also efficient both as a silencer and as contributing to the efficiency of the engine. It produces a slight increase in the number of revolutions of the engine per minute, whereas the effect of all mufflers heretofore used is to reduce the normal speed of the engine. And by removing the small bolts which attach the mouth of the Venturi tube to the forward conical stamping the venturi can, as already stated, be withdrawn from the casing and the whole muffler opened up for cleaning of deposited carbon without removal from the engine.

It is to be understood that the muffler may

be variously modified in its several details, within the scope of the appended claims, without departing from the principle or sacrificing the substantial advantages of the 5 invention.

What I claim as new, and desire to secure by Letters Patent, is—

1. A muffler for gas engines comprising a Venturi tube, an annular chamber surrounding the tube for substantially its entire length and communicating therewith through openings in the tube wall to the rear of its throat and an inlet to the chamber adapted to be attached to the exhaust of an 15 engine and to gradually spread and expand the exhaust gases and to deliver them directly into the chamber tangentially and in a thin stream extending substantially the length of the chamber, the chamber and the 20 openings in the tube wall permitting the exhaust gases to rotate freely and to further expand within the chamber.

2. A muffler for gas engines comprising an outer cylindrical casing, an integral 25 Venturi tube mounted therein and connected at each end therewith by a conical stamping, regularly distributed openings in the walls of the Venturi tube to the rear of its throat, and a single inlet carried by the outer casing 30 and arranged to receive the exhaust gases of an engine and to gradually spread and expand the same and deliver them tangentially in a thin stream through a longitudinal opening extending substantially the length 35 of the casing.

3. A muffler for gas engines comprising an outer casing substantially circular in cross-section, a Venturi tube mounted coaxially within the casing forming therewith 40 an annular chamber which surrounds the venturi substantially from end to end and is closed at both its ends, an intake connecting with and adapted to support the casing, which intake spreads the exhaust gases received at its outer intake end and delivers 45 them tangentially into the annular chamber through a narrow slit extending longitudinally of the chamber and having an area

greater than the area of the outer intake end, and an outlet from the chamber into the 50 Venturi tube which is provided by a number of small regularly distributed holes formed in the rear section of the tube wall to the rear of its throat and having an aggregate area of not less than the area of the inlet discharge 55 slit.

4. A muffler for gas engines comprising a Venturi tube with perforations in its walls to the rear of the throat, an annular chamber surrounding the Venturi tube which is 60 formed by an outer casing and two like conical stampings one connecting the mouth of the venturi with the forward end of the casing and the other providing an extension of and connecting the rear end of the venturi 65 with the rear end of the casing, a narrow longitudinal opening in the outer casing extending substantially the length thereof, and an inlet having an upper side which is shaped up from an integral tangential extension of the casing on one side of the said longitudinal opening and a lower side which is secured to the upper side along its edges and at its inner end is attached to the casing on the other side of the said longitudinal 75 opening.

5. A muffler for gas engines comprising an outer cylindrical casing which is provided with a longitudinal opening in the side thereof, two hollow conical members which 80 at their larger ends are fitted within and secured to the opposite ends of the casing and extend forwardly therefrom, the rear member within and the forward member beyond the casing, a Venturi tube which is perforated with holes to the rear of its throat and at its rear end is fitted with a slip joint within the smaller end of the rear conical member and at its mouth is fitted within and detachably secured to the smaller end of the 85 front conical member, and an inlet which is carried by the casing tangentially thereof and communicates therewith through the longitudinal opening in its side.

CHARLES WARD HALL.
